PUMP

Dwight L. Hopper, Wilkinsburg, Pa., assignor, by
mesne assignments, to the United States of
America, as represented by the United States
Atomic Energy Commission

Application October 12, 1944, Serial No. 558,355

6 Claims. (Cl. 230—101)

1

My invention relates to a pump and, particularly, to a construction for improving the operating characteristics of a multiple stage diffusion pump.

In the operation of multiple stage diffusion pumps, it is customary to provide a boiler compartment for each pumping stage of the pump. These boiler compartments have heretofore been separated by relatively thin metallic walls usually of spun material. Normally a pump has only one speed and an exhaust pressure dependent upon the air leak into the space being pumped. It has been customary to apply heat uniformly to all of the boiler compartments and when the rate of heating is changed, it is changed in all boiler compartments. However, the optimum operating conditions would be secured by applying different heat levels in the different boiler compartments.

According to my invention, this is accomplished by providing a separate heating element for each boiler compartment, the heating elements preferably being of the immersion type and the heat is prevented from transferring or migrating between the boiler compartments by using a heat insulating division between the boiler compartments.

I prefer to provide this heat insulating division by means of a double walled partition between the various boiler compartments and utilizing the double partition to provide a dead space which very effectively prevents the migration of heat between the boiler compartments so that they may be kept at different heat levels to secure the optimum operating characteristic of the pump.

It is an object of my invention to provide a multistage diffusion pump having improved operating characteristics.

A further object of my invention is to provide a pump boiler in which the boiler compartments may be maintained at different heat levels.

It is a further object of my invention to provide a multiple stage pump having different vapor pressures at the various pumping stages.

Other objects and advantages of my invention will be apparent from the following detailed description taken in conjunction with the accompanying drawing, in which:

Figure 1 is a sectional elevation of a pump embodying my invention; and

Fig. 2 is a similar view of a preferred embodiment of my invention.

In the exemplary embodiment of the pump according to Fig. 1, a multiple stage pump 1 is

herein shown as a two stage pump for simplicity. However, it is obvious that any number of stages may be similarly constructed. Each stage 2, 3 of the pump 1 is provided with a vapor evolving or boiler chamber 4, 5 and a conduit 6, 7 for conducting the vapor to a suitable diffusion nozzle 8, 9, the diffusion nozzles being surrounded by a cooled condensing surface 10. Each of the boiler chambers 4, 5 is provided with a heater member 11, 12 preferably of the electrical immersion type which is preferably mounted below the surface of the liquid and supported on suitable insulating devices such as ceramic blocks 13. The leads 14, 15 for the heating elements 11, 12 are brought out independently and the current through the heating elements 11, 12 may be adjusted by any suitable means (not shown).

The partition 25 between the boiler compartments 4, 5 is composed of a double walled device 20 preferably constructed of two concentric spinings 16, 17 welded or otherwise secured together to provide a hollow space 18 between the walls. In the modification according to Fig. 1, the hollow space 18 will normally be filled with the vapor 25 evolving material such as liquid oil, but in the confined space the liquid will be substantially dead or non-moving and, therefore, will transmit very little heat from one of the boiler compartments to the other. Passages 19 are provided for 30 transferring the liquid, such as oil from the condensing space through the boiler compartments 4, 5, as may be desired.

In the type of pump as shown, the condensate 35 is passed from the condensing chamber into the boiler compartment 5 connected to the high pressure pumping stage 3 where the low volatiles will be distilled off and operate in the high pressure or discharge stage 3 of the pump 1. The less volatile material will flow through the passage 19 40 into the low vacuum stage boiler 4 and will be utilized in the low vacuum or intake stage 2 of the pump. Preferably a dirt collecting barrier 20 is provided, usually in the form of a concentric ring secured to the bottom 22 of the outside 45 boiler compartments to prevent dirt from being drawn into the boiler compartments associated with the low pressure pumping stage.

In the preferred embodiment according to Fig. 2, the double walled partition 25 is sealed at each end providing an annular space filled with relatively motionless air which is even a better heat insulator than the oil-filled wall. The fluid passage 19 between the various boiler compartments is preferably constructed by means of grooves or channels in the base plate 22 of the boiler and

extending under the double walled partition 25. This type of oil channel presents a relatively long passage so that there will be very little tendency for the heat to transfer between the boiler compartments through the interconnecting channels 19.

In the operation of the pump according to the present embodiment of my invention, the heating elements 11, 12 of the various compartments 4, 5 will be adjusted to provide the optimum operating pressures for the various nozzles 8, 9 and the condensate from the nozzles 8, 9 will be returned to the vaporizing chamber 5 associated with the output or high pressure side 3 of the pump 1 where the low boiling material will be vaporized and delivered to the nozzle 9 of the high pressure stage 3 while the higher boiling materials will be vaporized in the boiler compartments 4 associated with the low vacuum or intake side 2 of the pump 1. The double boiler compartments substantially heat insulates the two vaporizing chambers 4, 5 from each other so that various heat levels may be maintained in either of the boiler compartments 4 or 5 without disturbing the heat level maintained in the adjacent compartments.

While for simplicity of illustration, I have shown and described preferred modifications of my invention it will be apparent to those skilled in the art that changes and modifications can be made therein without departing from the true spirit of my invention or the scope of the appended claims.

I claim as my invention:

1. A multistage vapor pump comprising a plurality of pumping stages, a boiler compartment for each pumping stage, heating means for each boiler compartment, and a double walled heat barrier between the boiler compartments.
2. A vapor pump comprising a plurality of serially operating pumping jets, a vaporizing compartment for each pumping jet, heating means

for controlling the vapor pressure at each pumping jet and a double walled partition between the vaporizing chambers.

3. A vapor pump comprising a plurality of serially operating pumping jets, a vaporizing compartment for each pumping jet, heating means for controlling the vapor pressure at each pumping jet and a double walled partition providing an air space between vaporizing chambers and a relatively long liquid passage between said vaporizing chambers.

4. A diffusion pump comprising a plurality of pumping stages, a boiler compartment for each pumping stage, means for heating the boiler compartments to different temperature levels and means for substantially thermally insulating the boiler compartments from each other.

5. A diffusion pump comprising a plurality of pumping stages, a boiler compartment for each pumping stage, means for heating the boiler compartments to different temperature levels, and a double walled portion between the boiler compartments to prevent heat interchange therebetween.

25 6. A vapor pump comprising a plurality of serially operating pumping stages, a vaporizing chamber for each pumping stage, individual heating means for each vaporizing chamber, a liquid passage between said vaporizing chamber and a dirt trap associated with said passage, and a thermal barrier between the vaporizing chambers.
